UNITED STATES PATENT OFFICE.

WESTON M. FULTON, OF KNOXVILLE, TENNESSEE, ASSIGNOR TO THE FULTON COMPANY, OF KNOXVILLE, TENNESSEE, A CORPORATION OF MAINE.

THERMOSTATICALLY-OPERATED RADIATOR CASING.

Application filed February 11, 1921. Serial No. 444,224.

To all whom it may concern:

Be it known that I, WESTON M. FULTON, a citizen of the United States, and a resident of Knoxville, Tennessee, have invented 5 new and useful Improvements in Thermostatically-Operated Radiator Casings, which invention is fully set forth in the following specification.

This invention relates to casings for radiators provided with thermostatically controlled means for regulating the flow of air therethrough and, therefore, their heating effect in the room or other compartment in which they are positioned.

15 It has heretofore been proposed to provide casings for radiators having thermostatically controlled means for regulating the flow of air therethrough in which the motor element of the controlling means is 20 positioned on the outside of the casing. Such constructions are illustrated, for example, in my prior Patents No. 1,256,220 granted Feb. 12, 1918, and No. 1,262,937 granted April 16, 1918. While capable of 25 controlling the flow of air through the radiator casing, devices of this type possess certain disadvantages which affect the extent of their use commercially, among the more important of which may be noted that, since 30 casings of this character are very generally used in residences, the projection of the motor element of the thermostat on the outside of the casing is more or less unsightly and inconvenient, whereby structures of this 35 character are objectionable in appearance to many persons owing to their necessarily unsymmetrical design; furthermore, radiators are frequently placed in recesses where there is little spare room for receiving a radiator 40 casing and the projection constituted by the motor element not infrequently makes it impossible to place a radiator casing with such a projection thereon in the recess; additionally, the projection of the thermostat 45 from the exterior of the casing subjects it to the danger of injury, particularly during shipment and installation, and at the same time adds to the expense of manufacture and, consequently, the initial cost of 50 the casing.

To avoid these disadvantages, it has been proposed, as in my reissued Patent No. 14,309 dated June 5, 1917 and my prior Patent No. 1,301,419 dated April 22, 1919, for 55 example, to so construct the radiator casing

as to provide therein a passage in which the thermostatic element may be positioned and through which a circulation of air may be induced. While avoiding the unsightly projection of the thermostatic motor element 60 from the exterior of the casing and the danger of its injury owing to such location, such structures still possess certain serious disadvantages which interfere with the extent of their use commercially. The provision of such a passage for receiving the thermostatic motor element in the interior of the casing results in an extension of the length of the casing which not only increases 65 its cost of manufacture but also increases 70 the space which it occupies to such an extent that its use with radiators positioned in recesses is not infrequently rendered impossible. Furthermore, where such a casing is used with relatively low radiators the 75 passage for receiving the thermostatic element and through which a circulation of air is induced is necessarily relatively short so that the circulation of air therethrough is apt to be sluggish and the response of 80 the thermostatic element to changes of room temperature is correspondingly sluggish. Again, the successful operation of a device of this character requires a continuous circulation of air through the passage which 85 contains the thermostatic element, whereby there is always an escape of heated air into the room although the temperature of the room be such as to cause the radiator casing to be otherwise closed; this may keep 90 the room overheated and be objectionable for that reason. Additionally, if the radiator be located in a recess, the body of air in such a recess is likely to be hotter than the air in the remainder of the room; as 95 it is the air in proximity to the casing that is drawn through the passage containing the thermostatic element, the latter is caused to respond more or less to the temperature of the recess rather than the temperature of 100 the room and, therefore, improperly regulates the temperature of the room itself.

It is an object of this invention to provide a casing for radiators provided with thermostatically controlled means for regulating the flow of air therethrough which, on the one hand, avoids the unsightly projection of the thermostatic motor element 105 from the exterior of the casing with its danger of injury and which, on the other 110

hand, avoids the disadvantages inherent in the location of the thermostatic element in an air passage within the radiator casing and through which a circulation of air is induced as above discussed.

A further object of the present invention is to provide a casing for radiators with thermostatically controlled means for regulating the flow of air therethrough in which the 10 thermostatic element will be more sensitive in its response to variations of air temperature than those heretofore employed for this purpose. The specific heat of air, as compared with liquids, is relatively low and it 15 therefore requires a relatively large volume of air in heat interchanging relation with the temperature responsive element of a thermostat to cause each unit of mass of said element to change its temperature per 20 degree. It is therefore of relatively great importance in the provision of a thermostat which is to respond to changes in air temperature that the thermosensitive medium employed be of relatively small volume or mass 25 so that the time lag thereof in responding to temperature changes shall be a minimum. It is therefore an object of this invention to provide in a device of the type characterized 30 thermostatic means which employs a relatively small mass of temperature responsive medium.

A further object of this invention is to provide a casing for radiators having thermostatically controlled means for regulating 35 the flow of air therethrough in which the thermostatic element utilizes the vapor of a volatile fluid for effecting its regulation of the controlling means and which at the same time will operate said controlling means 40 smoothly and regularly and with sensitivity to temperature changes in the air.

Other objects relate to the provision of a device of the type characterized in which the thermostatic element increases in sensitivity 45 as the temperature rises and which utilizes a vapor of a volatile liquid under such conditions that the vapor acts more nearly in accordance with the laws of expansion and contraction of perfect gases.

Still other objects relate to the provision 50 of a casing for radiators provided with thermostatically controlled means for regulating the flow of air therethrough which occupies a minimum of space, which is simple in construction and inexpensive to manufacture 55 and install, and which enables the temperature to be controlled sensitively and efficiently from any desired part of the room in which it is positioned.

Stated broadly, the invention comprises 60 a radiator casing provided with means for controlling the flow of air therethrough and means for operating said controlling means comprising a motor element in said 65 casing where it is subjected to the heat of

the radiator, said motor element being operatively connected to said controlling means, and a container for a thermosensitive fluid in communication with said motor element and positioned exteriorly of said casing where it is subjected to the temperature of the space to be heated. Said container is preferably charged with a relatively small volume of thermosensitive liquid which only partly fills the same, the remainder of the 70 space in said container and the space in the motor element and the communicating connections therebetween being filled with the vapor of said liquid, whereby said vapor in said motor element, being subjected to the 75 heat of said radiator and therefore maintained at a temperature above that to which said container is subjected, is superheated 80 with respect to the fluid in said container.

The invention is capable of receiving a variety of mechanical expressions, two of which are shown on the accompanying drawings, but it is to be expressly understood that the drawings are for purposes of illustration only and are not to be construed as a definition of the limits of the invention, reference being had to the appended claims for that purpose.

Referring in detail to said drawings wherein the same reference characters designate corresponding parts in the several figures:—

Fig. 1 is a more or less schematic perspective view illustrating an embodiment of the present invention and showing the temperature responsive element relatively remote from the radiator casing;

Fig. 2 is a vertical section illustrating another embodiment of the present invention in which the temperature responsive element is positioned on the exterior wall of the radiator casing, and also showing certain details of the dampers employed for controlling the flow of air through the casing;

Fig. 3 is a plan view of the embodiment of Fig. 2 with the top of the casing partly broken away to illustrate the construction of the dampers;

Fig. 4 is an enlarged face view of the motor element and its operating connections and adjustable controlling means; and

Fig. 5 is a vertical transverse section of the structure shown in Fig. 4 on the line 5—5 of said figure.

In the form shown, 1 is a radiator casing of any suitable construction provided in any suitable way with means for the ingress and egress of air. As illustrated in Fig. 1, the casing may have a suitable grilled or screened opening 2 adjacent the floor for admitting the cooler air, and louvres 3 or a grilled opening in the top wall or the upper portion of a side wall of said casing for permitting the escape of the air which has become heated by the radiator A. In order

to control the flow of air through the casing 1 and thereby regulate the heating effect of the radiator in the room or other compartment in which the same is located, 5 means of any suitable construction are mounted in or on the radiator casing 1, said means preferably taking the form of one or more dampers. In the form shown more particularly in Figs. 2 and 3, the upper portion 10 of the front wall of the casing 1 is provided in the rear of the louvres 3 with a plurality of apertures 4 with each of which cooperates a pivoted damper member 5. Said damper members may be of any suitable 15 construction and mounted in any suitable way. In the form illustrated, each of the apertures is provided with a peripheral inwardly directed flange 6 and each of the damper members 5 is composed of a flat body portion 7 provided with an outwardly directed flange 8 adapted to fit loosely over the inwardly directed flange 6 surrounding the opposed aperture 4. If desired, felt 9 may be clamped against the face of each 20 body portion 7 by suitable strips 10, said strips being of less area than the body of the damper members so as to leave exposed a marginal strip of said felt for engaging the edge of the opposed flange 6 when the 25 damper member is in closed position. With such a construction, practically no heated air can escape through the apertures 4 when the damper members 5 are moved into fully closed position. Each of the damper members 5, in the form shown, is provided with 30 pintles 11 which are pivotally mounted in lugs 12 suitably provided on the inner wall of the casing 1 in adjacency to the apertures 4. Each of the damper members 5 is also 35 provided with an upstanding pin or lug 13 for attachment to a short rod 14 which, at its opposite end, is pivotally connected to the operating bar 15 which extends the full length of the series of damper members. 40 Thereby said damper members are operatively connected to be moved in unison. 45 Any suitable means may be provided for operating said damper members. In the form shown, a rod 16 is pivotally connected 50 to the operating bar 15 at 17 and at its opposite end is pivoted at 18 to a lever 19 pivotally mounted at 20 on an upright 21 and pivotally connected at 22 to a rod 23 which is connected to a lever 24 which is actuated 55 by the thermostatic element to be described. 60 While a particular construction of radiator casing and means for controlling the flow of air therethrough has thus been described in detail, it is to be expressly understood that the invention is not limited thereto, as any suitable construction of radiator casing and means for controlling the flow of air therethrough may be employed in the present invention. 65 To actuate said means for controlling the

flow of air through said radiator casing, thermostatic means are operatively connected thereto and, in conformity with the present invention, said thermostatic means is composed of two elements:—a motor element 70 within the radiator casing where it is subjected to the heat of the radiator and a temperature responsive element which is located outside of the radiator casing where it is subjected to the temperature of the air 75 in the room or other space to be heated.

The motor element 25 may be of any suitable construction, but is preferably an expandable and collapsible vessel, being shown as composed of a corrugated, generally tubular side wall 26 closed at one end by a movable end wall 27 and at its opposite end by a stationary end wall 28. Said motor element 25 is mounted within the radiator casing 1 in any space that is available therefor or, as shown in Fig. 2, the radiator casing 1 may be slightly lengthened to provide a chamber 29 of sufficient size to receive the same. In any event, said motor element 25 should be mounted in adjacency 80 to the radiator so that it is subjected to the heat of the latter, although it is preferably not in direct contact therewith. Any suitable means for supporting the motor element 25 in position may be employed, that shown comprising a bracket 30 suitably attached to the end wall of the casing 1 and in turn supporting the upright 21, heretofore referred to, from which the stationary wall 28 of the motor element 25 is suitably 85 supported as by a plurality of posts 31.

The movable end wall 27 of the motor element 25 is operatively connected with the lever 24 in any suitable way. In the form shown, the movable end wall 27 is provided 105 with a plate 32 maintained in spaced relation from said end wall by one or more interposed posts 33, said plate 32 having a central boss 34 provided with a recess 35 in which engages a knife-edge projection 36 110 extending from the lever 24. Said lever is fulcrumed in any suitable way, being shown as engaging a knife-edge projection 37 suitably provided or mounted on the frame 38 of the motor element. 115

The expandable and collapsible vessel of the motor element 25 is in communication through a conduit 39 of any suitable size and construction, it preferably being small and flexible, with a container 40 which is 120 designed to receive a thermosensitive fluid and which constitutes the temperature responsive element heretofore referred to. Said container 40 is preferably of relatively small volume and may desirably take the form of 125 a tubular bulb as illustrated in Figs. 1 and 2. Said container 40 is mounted exteriorly of the radiator casing 1 and it may be positioned in any desired location for subjection to the temperature of the air in the 130

room or other space to be heated. In the form shown in Fig. 1, the container 40 is mounted on the wall on the opposite side of the room from the radiator A and is connected to the motor element through the long pipe 39 which, to protect it from injury and conceal it from sight, preferably extends within the wall and under the floor as diagrammatically illustrated. In the form shown in Fig. 2, the container 40 is mounted on the end wall of the radiator casing 1 and the tube 39 is not only of sufficient length to extend from the container 40 to the vessel of the motor element 25 but it is an essential feature of this invention that the length of tube 39 should be sufficient to prevent the conduction of heat from the motor element to the container 40 to a material degree. In order to still further insure against the container 40 receiving heat by conduction from the motor element through pipe 39, it is preferable that a greater or less portion of tube 39 should be exposed to the atmosphere outside of the casing between said casing and the point where said container is mounted on the wall of the casing. The tube or pipe 39 may be made either rigid or flexible and, if desired, it may be protected in any suitable way. The container 40 is preferably surrounded by a small housing 41 to protect the same from injury, said housing being suitably apertured so that air at room temperature may have ready access to the container 40. When the container 40 is mounted on the wall of the radiator casing, it should preferably be protected from the effects of heat conducted through the wall of the radiator casing. Any suitable means may be provided for insulating the container 40 from the heat on the inside of the radiator casing, the end wall of the casing in the construction shown in Fig. 2 being heavily lagged at 42 to prevent the transference of heat through said end wall to the container mounted thereon.

Any suitable means may be associated with the motor element 25 to predetermine the temperature at which the thermostatic element will respond to temperature changes and effect the opening or closing of the damper members 5. In the form shown, the lever 24 is extended at 43 and connected through a separable connection at 44 to an arm 45 extending upwardly from a transverse bar 46 which is mounted to rock on knife edges 47 extending from the framing 38 of the motor element. A hook-like member 48, also supported from the framing of the motor element, may be extended under the bar 46 to prevent its dropping away from the knife edges 47. Said transverse bar 46 is also provided with a laterally extending arm 49 to which is connected one end of a coil spring 50, the opposite end of which

spring is connected to one end of a lever 51 which is pivoted at 52 to an upstanding arm 53 and is bifurcated intermediate its ends at 54 to receive and retain a pivoted nut 55 which works on the threads of a screw 56. Said screw 56 is pivotally mounted at its lower end 57 in a block 58 suitably retained on the framing of the motor element, and at its upper end extends through the top wall of the radiator casing 1 as shown at 59, where it may be squared, or otherwise suitably shaped, as shown at 60 to receive means for rotating the same. It therefore becomes apparent that the rocking of the transverse bar 46 on its knife edge fulcrums 47, and therefore the expansion of the motor vessel 25, is opposed by the tension of the spring 50, and the tension of said spring may be adjusted by rotating the screw 56 to vary the position of the lever 51.

The adjustment of the screw 56 and the parts actuated thereby may be indicated in any suitable way. In the form shown, a finer thread 56' on the screw 56 cooperates with a non-rotatable nut 55' which carries a pin 61 that works in a cam slot 62 in a sleeve 63 which surrounds the screw and is provided with a boss 64 which extends through the top wall of the radiator casing 1 and carries, suitably connected thereto in any suitable way, a pointer 65 designed to cooperate with suitable indicia provided on the top wall of the casing 1 or on an index plate 66 connected thereto.

If desired, the operating connections from the motor element to the damper members may be provided with toggle mechanism for the purpose fully described in my prior Patent No. 1,186,180 granted June 6, 1916. In the form shown, the transverse rocking bar 46 is provided with an upstanding arm 67, recessed at its upper end as shown at 68, where it is engaged by the knife edge end 69 of a downwardly extending bar 70 which is engaged with or connected to a pivotally mounted arm 71 that has connected thereto, at a point between its fulcrum and its point of engagement with said bar 70, a coil spring 72 connected at its lower end with an adjustable screw or bolt 73.

The container 40 is charged with any suitable volatile liquid, said volatile liquid by preference only partly filling the same. The remainder of the space within said container 40 and the space in the tube or pipe 39 and the motor vessel 25 (which is in open communication through said tube or pipe 39 with the container 40) are filled with the vapor of said liquid. As the motor vessel 25 is enclosed within the radiator casing 1 and subjected to the heat of the same, whereas the container 40 is mounted exteriorly of the radiator casing where it is subjected to the temperature of the air in the room, the motor vessel is always at a temperature

above that of the container so that the vapor in said motor vessel is superheated as respects the temperature of the volatile fluid in the container. As the temperature of the air in the room rises the temperature of the volatile liquid in the container 40 correspondingly rises and, as the mass of this liquid in this container is relatively small, the temperature of said liquid is able to follow 10 sensitively and with a minimum time lag the changes of temperature in the air in the room—notwithstanding the relatively low specific heat of air. A rise in temperature of the volatile liquid in the container 40 is 15 accompanied by the evaporation of some of the liquid therein and a corresponding increase in the tension of the vapor in said container and in the motor vessel communicating therewith. Some of this vapor also 20 flows into the motor vessel where it becomes superheated by the heat of the radiator and said vapor therefore undergoes a further expansion. In fact, the vapor in the motor vessel 25, being superheated, acts more like 25 a perfect gas when expanding and contracting. When the increase in vapor tension in the motor vessel 25 is sufficient to overcome the tension of the spring 50, said vessel begins to expand and, through the operating 30 connections from its movable end wall 27, to close the damper members 5.

On the other hand, if the temperature of the air in the room begins to fall, the temperature of the liquid in the container 40 35 correspondingly falls, and the vapor tension in said container is correspondingly reduced as is also the vapor tension in the motor vessel 25. The tension of the spring 50 on the movable end wall 27 of said vessel 40 causes the latter to collapse and, through the operating connections from said movable end wall, the damper members 5 are opened. During the collapse of the motor element some of the vapor contained therein is forced 45 into the container 40 and, its temperature being reduced to that of the room in the latter, there is a contraction in the volume of this vapor as well as a condensation of some of the vapor.

50 It will therefore be perceived that a radiator casing has been provided with thermostatically controlled means for regulating the flow of air therethrough in which the thermostatic element need employ only a 55 relatively small mass of temperature responsive medium:—the container 40 need be supplied with only a relatively small volume of volatile liquid; in fact the volume of liquid provided in said container need be 60 only slightly, if any, in excess of that sufficient to provide a volume of vapor equal to the volume of said container, the communicating tube or pipe 39 and the motor vessel 25 in its fully extended position. 65 This small volume of liquid is sensitively

responsive to temperature changes, so that the time lag is reduced to a minimum. At the same time, as the temperature of the vapor in the motor vessel 25 is always maintained above that of the fluid in the container 40, there is a two-fold expansion or contraction of said vapor as the temperature rises and falls, enabling a smaller quantity of volatile liquid to be used than if said vapor in the vessel 25 were not superheated 70 and caused to follow more closely the law of perfect gases in its expansion and contraction.

It will also be perceived that the container 40 may be placed at any desired location 75 within the room where it will be sensitively responsive to temperature changes therein. Thus, if the radiator be located in a recess between pilasters as shown in Fig. 1, so that the temperature of the air in said recess is 80 likely to be above that in the rest of the room, the container 40 may be located at a point relatively remote from the radiator where it will respond to the true temperature 85 of the air in the room and still effectively 90 and sensitively control the dampers of the radiator casing. At the same time, if the radiator be relatively low, the container 40 may be so positioned that it will respond 95 sensitively to changes in the room temperature without the difficulties heretofore experienced owing to sluggish circulation when the thermostatic element is positioned in a short passage of a low radiator casing.

It is to be understood that whether the container 40 be mounted on the wall of the radiator casing or at some point more or less remote therefrom, it is to be so connected 100 with the motor vessel that the volatile liquid will remain in said container and preferably 105 only the vapor of said liquid flow through the communicating tube or pipe 39 to the motor vessel 25.

It will also be perceived that a casing has 110 been provided for radiators which is simple in construction and inexpensive to manufacture and install. Additionally, the radiator casing occupies little if any more space than the radiator itself and is therefore available for use with radiators located 115 in recesses where there is little spare room around the same. On the other hand, the use of unsightly projections on the radiator casing has been avoided and the 120 thermostatic motor element is, at the same time, so arranged that it is protected from injury during shipping and installation.

While a suitable construction for operating dampers from the motor vessel and for predetermining the temperature at which said dampers will respond to temperature changes has been described with considerable detail it is to be expressly understood 125 that the form illustrated and described is not essential to the present invention, such 130

having been selected as simply illustrative of one suitable construction for these purposes. Changes may also be made in the details of construction and arrangement of parts without departing from the spirit of this invention. The illustrative embodiments of the present invention having been described above with considerable particularity, other embodiments thereof will now readily suggest themselves to those skilled in the art as the same is capable of receiving a variety of mechanical expressions, while certain features thereof may be used without other features thereof. For example, where a radiator is installed in a recess, as illustrated in Fig. 1, the walls of the recess may constitute a portion of the enclosure, or casing, as is now common in engineering practice, and the term "casing" as herein used is intended to include such or other equivalent structures. Reference is therefore to be had to the claims hereto appended for a definition of the limits of the invention.

25. What is claimed is:—

1. In combination with a radiator casing provided with means for controlling the flow of air therethrough, means for operating said controlling means including a thermostat comprising a motor element in said casing where it is maintained by the radiator at a temperature above that in the space to be heated, said motor element being operatively connected to said controlling means, and a container for a thermosensitive fluid in communication with said motor element and positioned exteriorly of said casing where it is subjected to the temperature of the space to be heated.

40. 2. In combination with a radiator casing provided with means for controlling the flow of air therethrough, means for operating said controlling means including a thermostat comprising an expansible and collapsible vessel positioned in said casing where it is maintained by the heat of the radiator at a temperature above that exteriorly of said casing, said vessel having its movable wall operatively connected to said controlling means, and a container for a volatile fluid communicating with said vessel and positioned exteriorly of said casing.

55. 3. In combination with a radiator casing provided with means for controlling the flow of air therethrough, means for operating said controlling means including a thermostat comprising a motor element in said casing heated by the radiator and operatively connected to said controlling means and a container for a volatile liquid positioned exteriorly of said casing and communicating with said motor element, said motor element containing the vapor of said liquid.

65. 4. In combination with a radiator casing provided with means for controlling the flow

of air therethrough, means for operating said controlling means including a thermostat comprising an expansible and collapsible motor element in said casing heated by the radiator and operatively connected to said controlling means and a container for a volatile liquid positioned exteriorly of said casing and communicating with said motor element, said container being partly filled with said volatile liquid and said motor element containing the vapor of said liquid and communicating with the vapor space in said container.

5. In combination with a radiator casing provided with means for controlling the flow of air therethrough, means for operating said controlling means including a thermostat comprising a vaporizing chamber containing a relatively small quantity of volatile liquid positioned exteriorly of said casing and communicating with a motor element positioned in heat-interchanging relation with the radiator, said motor element being operatively connected to said controlling means.

6. In combination with a radiator casing provided with means for controlling the flow of air therethrough, means for operating said controlling means including a thermostat comprising a vaporizing chamber containing a relatively small quantity of volatile liquid positioned exteriorly of said casing and communicating with a motor element operatively connected to said controlling means, said motor element containing the vapor of said liquid and being in heat-interchanging relation with said radiator whereby it provides a superheating chamber for the vapor of said liquid.

7. In combination with a radiator casing provided with means for controlling the flow of air therethrough, means for operating said controlling means including a thermostat comprising a container for a volatile liquid positioned exteriorly of said casing and a motor element operatively connected to said controlling means and communicating with said container, said motor element being in heat-interchanging relation with the radiator and so related to said container as to contain only the vapor of said liquid.

8. In combination with a radiator casing provided with means for controlling the flow of air therethrough, means for operating said controlling means including a thermostat comprising an exterior container having therein a volatile liquid and a motor element communicating with said container and positioned in heat-interchanging relation with the radiator, said motor element being operatively connected to said controlling means.

9. In combination with a radiator casing provided with means for controlling the flow of air therethrough, means for operat-

ing said controlling means including a thermostat comprising a container partly filled with a volatile liquid and having a vapor space therein, said container being positioned exteriorly of said casing, and a motor element in said casing where it is heated by the radiator, said motor element being in communication with said vapor space and operatively connected to said controlling means.

10 10. In combination with a radiator casing provided with means for controlling the flow of air therethrough, means for operating said controlling means including a thermostat comprising a container having therein a relatively small volume of volatile liquid and positioned exteriorly of said casing and a motor element communicating with said container and containing only the vapor of said liquid, said motor element being operatively connected to said controlling means and positioned in said casing where it is subjected to the heat of the radiator whereby said vapor is maintained at a higher temperature than the liquid in said container.

15 11. In combination with a radiator casing provided with means for controlling the flow of air therethrough, means for operating said controlling means including a thermostat comprising an exterior container having therein a volatile liquid and an interior motor element in communication with said container and containing only the vapor of said liquid, said motor element being operatively connected to said controlling means.

20 12. In combination with a radiator casing provided with means for controlling the flow of air therethrough, means for operating said controlling means including a thermostat comprising an exterior container having therein a volatile liquid and an interior motor element in communication with said container and containing the superheated vapor of said liquid, said motor element being operatively connected to said controlling means.

25 13. In combination with a radiator casing provided with means for controlling the flow of air therethrough, means for operating said controlling means including a thermostat comprising a vaporizing chamber outside of said casing and containing a volatile liquid and a motor element inside of said casing and maintained by the radiator at a temperature above that at the out-

side of said casing, said motor element communicating with the vapor space in said vaporizing chamber and being operatively connected to said controlling means.

60

5 14. In combination with a casing for a radiator and means for controlling the escape of heated air therefrom, means for operating said controlling means comprising a thermostat including a vaporizing chamber for a volatile liquid positioned exteriorly of said casing where the vapor tension in said chamber is controlled by the temperature of the space to be heated, a motor element containing the vapor of said liquid and positioned interiorly of said casing where it is maintained by the radiator at a higher temperature than that of said chamber, a conduit whereby said motor element is in communication with said vaporizing chamber, and operative connections between said motor element and said controlling means.

70

75

15 15. In combination with a casing for a radiator and means for controlling the escape of heated air therefrom, means for operating said controlling means comprising a thermostat including a chamber containing a relatively small quantity of volatile liquid and a vapor space, said chamber being positioned exteriorly of said casing where it is subjected to the temperature of the space to be heated, a tube communicating with said vapor space, a motor element communicating with said tube and positioned in said casing where it is heated by said radiator, and operative connections between said motor element and said controlling means.

80

85

90

20 16. In combination with a casing for a radiator and means for controlling the escape of heated air therefrom, means for operating said controlling means comprising a thermostat including a container for a volatile liquid positioned exteriorly of said casing where it is subjected to the temperature of the space to be heated, an expansible and collapsible motor element containing the vapor of said liquid and positioned in said casing adjacent said radiator whereby said vapor is heated to a higher temperature than said liquid, said motor element communicating with said container, and operative connections between said motor element and said controlling means.
